UNITED STATES PATENT OFFICE.

IRVIN BELFORD, OF CALDWELL, OHIO.

IMPROVEMENT IN HAND-RESTS.

Specification forming part of Letters Patent No. 136,357, dated March 4, 1873.

To all whom it may concern:

Be it known that I, IRVIN BELFORD, of Caldwell, in the county of Noble and State of Ohio, have invented certain new and useful Improvements in Hand-Rests; and I do hereby declare the following to be a full, clear, and exact description of the invention, such as will enable others skilled in the art to which it pertains to make and use it, reference being had to the accompanying drawing, which forms part of this specification.

My invention relates to hand-rests for the use of recorders, book-keepers, and others; and consists of a plate attached to mechanism by which it may be raised or lowered to the desired height, so that the writer's hand, resting upon said plate, shall be level with the surface to be written upon.

In the drawing, Figure 1 is a side elevation of my invention; and Fig. 2, a view in perspective of the same, showing its application.

A is a plate of wood, metal, or other suitable substance, to which are attached the journals B B, in which turns the right and left hand screw-rod C. Upon the screw-rod C runs the arms D D, perforated by a female screw to correspond with the threads of the rod C.

Attached to the ends of the arms D D are the legs E E, crossing and connected at e. It will be seen that when the screw-rod C is turned by the key G the arms D D will either be brought together or sent apart by the opposing screws, according as the rod C is turned, thus inclining the legs E E more or less to the horizontal, and consequently raising or lowering the plate A.

I do not confine my invention exclusively to the article of hand-rests, as it may be applied to tables, desks, chairs, leaf-support to books, &c.

Having thus described my invention, what I claim as new, and desire to secure by Letters Patent, is—

The combination of the plate A with the journals B B, the right and left hand screw-rod C, the arms D D, and the legs E E, substantially as and for the purpose set forth.

In testimony that I claim the foregoing I have hereunto set my hand this 24th day of January, 1873.

IRVIN BELFORD.
